ADVERTISING DISPLAYS
Irwin Herbert Kravitz, 8 S. 46th St.,
Philadelphia, Pa. 19134
Filed Dec. 6, 1965, Ser. No. 511,627
10 Claims. (Cl. 40—33)

This application is a continuation in part of my prior application, filed Oct. 4, 1965, Serial No. 492,600, for Advertising Display.

This invention relates to advertising displays and more particularly to activated displays in which the driving mechanism is concealed from view in a manner such that observers are unable to ascertain the source of motive power and the mode of actuation of moving parts.

It has heretofore been proposed as in the Horton Patent No. 1,728,610, to provide a display device in which an object is rotated in front of an inclined mirror, by a drive shaft extending through the mirror to the driving mechanism behind the mirror. This structure has serious shortcomings not only as to the limited character of display but because of the limitations inherent in piercing a mirror.

It has also heretofore been proposed as in the Behning Patent No. 1,729,472, to utilize the intersection of two vertical mirrors disposed at right angles. Extreme precision of shaping of the rotating element and close tolerances as to the sizes of the rotating element and opening in which it is disposed are essential to preserve the illusion. Such precision is difficult to attain and there still remains the relative motion of the peripheral edge of the rotating element which readily indicates the disposition of the concealed part of the rotating element.

It is the principal object of the present invention to provide advertising displays having moving objects with improved concealment of the actuating mechanism.

It is a further object of the present invention to provide advertising displays having moving objects and in which a variety of objects can be selectively employed.

It is a further object of the present invention to provide advertising displays having concealed driving mechanism with a maximum of concealment and which are of simple but effective construction.

It is a further object of the present invention to provide advertising displays which embody an apparently empty box with thin walls and with respect to which objects are supported and move with no visible means of support and/or actuation.

It is a further object of the present invention to provide an advertising display which embodies an apparently empty box with thin walls and spaced above a shelf or the like, with a moving object in the interior thereof and with a plurality of moving and changing messages.

It is a further object of the present invention to provide in an advertising display of the character aforesaid, interior illumination the wiring for which is also concealed.

It is a further object of the invention to provide an advertising display which embodies an apparently empty box with thin walls and with a moving object in the interior thereof without visible means of support or of actuation, the walls of the box being decorated in a manner to enhance the appearance of emptiness.

Other objects and advantageous features of the invention will be apparent from the description and claims.

The nature and characteristic features of the invention will be more readily understood from the following description taken in connection with the accompanying drawings forming part thereof, in which:

FIGURE 1 is a view in perspective of an advertising display in accordance with the invention;

FIG. 2 is a vertical sectional view from front to rear taken approximately on the line 2—2 of FIG. 1;

2

FIG. 3 is a horizontal sectional view taken approximately on the line 3—3 of FIG. 2;

FIG. 4 is a vertical sectional view taken approximately on the line 4—4 of FIG. 2;

5 FIG. 5 is a fragmentary vertical sectional view, taken approximately on the line 5—5 of FIG. 2; and

FIG. 6 is a fragmentary horizontal sectional view taken approximately on the line 6—6 of FIG. 2.

It should, of course, be understood that the description and drawings herein are illustrative merely, and that various modifications and changes can be made in the structure disclosed without departing from the spirit of the invention.

Like numerals refer to like parts throughout the several views.

Referring now more particularly to the drawings, a receptacle 10 in the form of a box is shown having horizontal top and bottom walls 11 and 12, vertical side walls 13 and a vertical rear wall 14 which is never within the view of an ordinary observer of the display. The front of the receptacle 10 is open and substantially unobstructed so as to permit of looking into the interior of the receptacle 10. The front of the receptacle 10 may have a transparent wall 15 to reduce the entry of dust into the interior without interfering with viewing the interior.

The top, bottom and side walls 11, 12 and 13 are preferably made of relatively thin material, particularly as compared with the front opening of the receptacle, so as to make it clear from observation that no motor or other power mechanism is capable of being concealed in the walls. The walls 12, 13 and 14 may be held together by angular binding strips 16. The bottom wall 12 can be supported on V-shaped feet 17 of strap material so that the space below the bottom wall 12 and in and around the feet 17 can be readily observed. A collapsible carrying handle 18 can be secured to the top wall 11.

In order to provide an open space within the receptacle 10 side wall reflecting members are provided, preferably comprising two vertical mirrors 20 disposed in perpendicular planes with their front edges 21 beveled and meeting at a right angle (see FIG. 6) and in a line connecting the center of the top wall 11 with the center of the bottom wall 12. The rear edges 22 of the mirrors 20 are thus at the respective edges at which the side walls 13 meet the rear wall 14.

The mirrors 20 are preferably positioned and supported by wooden backing strips 23 and a mirror backing sheet 24 may also be employed.

50 Metal frame elements 27 are provided, of angle cross section extending along the rear faces of the mirrors 20, with vertical flanges 25.

55 The interiors of the side walls 13 can have any desired finish but a preferred covering is of corrugated sheet material, as at 29, with the corrugations vertical. The sheet material can be paper, metallic foil or other desired material.

60 A concealed space 30 is accordingly provided, to the rear of the mirrors 20, in front of the rear wall 14, and between the top and bottom walls 11 and 12.

Within the space 30 and carried on a frame bar 31, which is supported on horizontal flanges 32 of the frame elements 27, an electric motor 35 is provided. The motor 35 is preferably of slow speed type or with a built-in speed reducer, and has a vertical shaft 36. The shaft 36 has a belt driving roller 37 secured thereto which engages with an endless band or belt 38 disposed for movement in a horizontal path. The exposed face of the belt or band 38 can have an advertising message displayed thereon, successive portions of which are advanced to a position to be read from the position of an observer looking into the front of the box 10.

The band 38 is guided and supported by rear flanged guide rolls 39 carried by the frame elements 27, and intermediate guide rollers 40 carried by a bracket 34 on a horizontal frame bar 41 (see FIG. 5).

A pressure roller 42 is provided carried on a stub shaft 43 which is slightly movably or deflectably supported on a post 44 bolted to the bottom wall 12. The roller 42 is urged by a tension spring 46 secured to the shaft 43 and to the frame bar 31 to a position to increase the tension of the belt 38 and the length thereof which is in engagement with the roller 37, thereby providing a more positive drive.

The frame bar 41 has a vertical frame bar 45 secured thereto which is mounted at its lower end on the bottom wall 12.

The frame bar 41 extends forwardly through a concealed opening 48 at the meeting front edges 21 of the mirrors 20 and supports a fixed vertical shaft 49 on which upper and lower dished plates 50 and 51 are carried on bearings 52. The plates 50 and 51 have grooved portions 53 and 54 in which the band or belt 38 is seated.

The upper dished plate 50 has a peripheral face 55 on which an advertising message can advantageously be displayed for continuous advancing to a position for viewing upon turning of the plate 50, and an upper face 56 on which an article to be displayed can be carried.

The band or belt 38 is also preferably held in position in the grooved portions 53 and 54 by front rollers 58 which are carried by the frame bar 41 in the same manner as the rollers 40.

It will be noted that the dished plates 50 and 51 are of such diameter and are so arranged that they effectively conceal as viewed from the front of the box 10, the opening 48 as well as the rollers 58 and their supporting structure.

At the upper and lower front margins of their inner faces of the side walls 13, upper and lower light screens 60 and 61 can be provided behind which electric lamp sockets 62 and incandescent lamps 63 are located, the wiring (not shown) running to the rear space 30 and being concealed between the sheets 29 and the side walls 13.

A switch 65 can be provided, on the concealed rear wall 14 for controlling the energization of the motor 35 and/or the lamps 63, the conductor (not shown) controlled by the switch 65 extending from the rear wall 14 so that it cannot be seen from an observer in front of the box 10.

The manner of use will now be pointed out.

The box 10 is preferably placed in a store window or on a shelf, or at any other appropriate location at which the front of the box 10 faces toward the observer, the rear wall 14 cannot be seen, and the electrical conductor for supplying energy cannot be seen by the observer.

Rotation of the motor shaft 36 is effective for driving the belt or band 38 which continuously drives the dished plates 50 and 51 but without any special emphasis on how the plates 50 and 51 are rotated.

An article (not shown) placed on the upper face 56 of the plate 50 is turned so that its sides are necessarily displayed to an observer.

The continuous movement of the band 38 and the periphery of the plate 50 successively bring to the observer the messages thereon.

The disposition of the dished plates 50 and 51, and the band 38 is such that their actuating mechanism cannot be seen by an observer in front of the box 10.

The mirrors 20 effectively conceal the space 30 and the operating mechanism therein contained.

It will thus be seen that apparatus has been provided for attaining the objects of the invention.

I claim:

1. An animated display device comprising

a receptacle having top, bottom and side walls and an open front,

a mirror member interiorly disposed in said receptacle and having portions extending at an angle of 45° with respect to at least two of said walls and disposed with respect to said top wall to provide a rear interior concealed space bounded in part by said top wall,

a rotatable display member exteriorly and forwardly disposed with respect to said space, and mounted on an upright axis for rotation, motor means in said space,

driving connection, driven by said motor means and including an endless band extending through said mirror member and in driving engagement with said rotatable member, said rotatable member being in concealing relation to the location at which said band extends through said mirror member.

2. An animated display device as defined in claim 1 in which

said rotatable member includes a dished plate having a peripheral message display rim.

3. An animated display device as defined in claim 1 in which

said rotatable member includes a dished plate having an upper article display face.

4. An animated display device as defined in claim 1 in which

said rotatable member has a seating rim portion in which said band is engaged.

5. An animated display device as defined in claim 1 in which

guide rollers are provided interiorly and exteriorly of said mirror member for guiding said band, and said rotatable member is in visual concealing relation to said exteriorly disposed guide rollers.

6. An animated display device as defined in claim 1 in which

said space has mounted therein resiliently urged tensioning roller in engagement with said band.

7. An animated display device as defined in claim 1 in which

said side walls along the interior thereof have a corrugated covering for reflection by said mirror member.

8. An animated display device as defined in claim 1 in which

a frame member is provided in said space, and said frame member has a forwardly extending portion intersecting said mirror member and on which said rotatable member is carried.

9. An animated display device as defined in claim 8 in which

said forwardly extending portion has guide rollers for said band carried thereby, and said rotatable member is in visual concealing relation to said guide rollers.

10. An animated display device as defined in claim 1 in which

light sources are provided within said receptacle and forwardly of said mirror member for illuminating the visible interior part of said receptacle.
